UNITED STATES PATENT OFFICE.

JOHN WESLEY CARPENTER, OF BRIDGEWATER, VIRGINIA.

COMBINED BURGLAR-ALARM AND SASH-LOCK.

No. 868,529.

Specification of Letters Patent.

Patented Oct. 15, 1907.

Application filed June 29, 1906. Serial No. 324,067.

To all whom it may concern:

Be it known that I, JOHN WESLEY CARPENTER, a citizen of the United States, residing at Bridgewater, in the county of Rockingham and State of Virginia, 5 have invented a new and useful Combined Burglar-Alarm and Sash-Lock, of which the following is a specification.

This invention relates to combined window sash fasteners and burglar alarms.

10 The object of the invention is to provide means for locking the window in partially opened position thereby to permit ventilation of the room, and means for sounding the alarm should an attempt be made by an unauthorized person to enter the room by raising or 15 lowering the sash when the locking member or fastener is moved to inoperative position.

A further object of the invention is to generally improve this class of devices so as to increase their utility, durability and efficiency as well as to reduce the cost 20 of manufacture.

With these and other objects in view the invention consists in the construction and novel combination and arrangement of parts hereinafter fully described, and illustrated in the accompanying drawings, it being 25 understood that various changes in form, proportions and minor details of construction may be resorted to within the scope of the appended claims.

In the accompanying drawings forming a part of this specification: Figure 1 is a perspective view of a portion 30 of a window provided with a combined sash-fastening and burglar alarm constructed in accordance with my invention. Fig. 2 is a top plan view of the alarm or bell with the cover removed. Fig. 3 is a side elevation showing the position of the pivoted trip when 35 the sashes are operated.

Similar numerals of reference indicate corresponding parts in all of the figures of the drawings.

The improved device is principally designed for use 40 on sliding closures such as window sashes, transoms and the like and by way of illustration is shown in connection with a window of the ordinary construction in which 5 designates the lower sash and 6 the upper sash slidably mounted in the frame or casing 7, as shown. Secured to the parting rail 8 of the lower sash 45 5 is an alarm preferably in the form of a bell 9 the base of which is provided with a depending attaching bracket 10 adapted to be secured to the upper face of the parting rail in any suitable manner as by screws or similar fastening devices 11. The bell is provided 50 with the usual pivoted actuating lever 12 and hammer 13, there being a spring 14 secured to the lever for returning the latter to normal position after each movement of the same. The lever 12 is extended beyond the pivot point 15 and is provided with a pair of spaced

depending ears 16 between which is pivotally mounted 55 a rod or trip 17 adapted to engage an actuating member 18 carried by the upper sash 6. The actuating member 18 is secured to one of the vertical rails of the upper sash and consists of a plate provided with an angular extension 19 having an inclined or cam face 20 60 adapted to engage the trip 17 when either sash is moved to open or partially open position and sound the alarm.

As a means for locking either sash in partially open position thereby to permit ventilation of the room there is provided a locking member 21 pivoted at 22 above 65 the actuating member 18 and having its free end provided with an inclined face 23 defining a depending lip 24 adapted to engage the parting rail 8 of the lower sash and thereby prevent further movement of said sashes. The lip 24 extends in the path of movement of 70 the lower sash 5 and is provided with a shoulder 25 which bears against the actuating member 18 and serves to limit the lateral movement of said locking member.

Attention is called to the fact that the short end of the rod or trip 17 normally bears against the bottom of 75 the lever 12 thereby to hold the trip rigid and in alignment with the lever when said trip is moved in engagement with the inclined face 20 so that the lever will be moved laterally on the upward movement of the lower sash, the pivotal connection between the lever and the 80 trip permitting the latter to move to the position shown in Fig. 3 of the drawings when the sash is lowered.

The actuating member 18 is preferably disposed a short distance above the parting rail 8 so as to permit either sash to be moved to partially open position thereby to permit ventilation of the room without actuating 85 the alarm.

When the locking member 21 is moved to inoperative position, as indicated by dotted lines in Fig. 1 of the drawing, an attempt by an unauthorized person 90 to open the window and obtain access to the interior of the room will cause the trip 17 to engage the inclined face 20 of the actuating member and move the lever 12 laterally against the tension of the spring 14 so that when the trip clears the upper end of said member the 95 spring will return the lever to normal position and thereby sound the alarm. When the sash is lowered the trip 17 will engage the top of the actuating member thereby tilting the same and permitting the sash to be readily lowered without sounding the alarm. 100

When it is desired to lock either sash in open or partially open position the locking member 21 is moved downwardly in engagement with the actuating member 18 thereby causing the lip 24 to extend in the path of movement of the lower sash and limit the upward 105 movement of the same.

From the foregoing description it will be seen that there is provided an extremely simple, inexpensive and

efficient device admirably adapted for the attainment of the ends in view.

Having thus described the invention what is claimed is:

- 5 1. The combination with a pair of sliding sashes, of an actuating member secured to one of said sashes and provided with an inclined face, an alarm secured to the adjacent sash and provided with an operating lever, and a trip pivotally mounted on said lever and adapted to engage 10 the inclined face of the actuating member thereby to sound the alarm, said trip being locked against tilting movement in one direction and free to tilt in the opposite direction.
2. The combination with a pair of sliding sashes, of an actuating member secured to one of the sashes and provided with an inclined face, an alarm secured to the adjacent sash and provided with an operating lever the free 15 end of which is bifurcated to form a pair of depending ears, and a trip pivotally mounted between said ears and adapted to engage the inclined face of the actuating member for sounding the alarm, said trip being free to move in one direction and locked against movement in the opposite direction.
3. The combination with a pair of sliding sashes, of an actuating member secured to one of said sashes and provided with an inclined face, an alarm secured to the adjacent sash and provided with a pivoted operating lever 20 the free end of which is bifurcated to form a pair of spaced depending ears, and a trip pivotally mounted between said ears and having its short end normally bearing against the lever for locking the trip against movement in one direction.

30

rection, the free end said trip being extended in the path of movement of the actuating member thereby to operate the lever and sound the alarm.

4. The combination with a pair of sliding sashes, of an actuating member secured to one of said sashes and provided with an inclined face, of an alarm secured to the adjacent sash and provided with a pivoted trip adapted to engage the inclined face of the actuating member for sounding the alarm, said trip being free to tilt in one direction and locked against tilting movement in the opposite 40 direction, and a locking member pivotally mounted on one of the sashes and movable to operative position in the path of movement of the adjacent sash.

5. The combination with a pair of sliding sashes, of an actuating member secured to one of the sashes and provided with an inclined face, an alarm carried by the adjacent sash and provided with a pivoted trip adapted to engage the inclined face of the actuating member for sounding the alarm, said trip being free to tilt in one direction and locked against tilting movement in the opposite 45 direction, and a locking member pivotally mounted on one of said sashes and provided with a lip extending in the path of movement of the lower sash and defining a shoulder adapted to bear against the actuating member.

In testimony that I claim the foregoing as my own, I have hereto affixed my signature in the presence of two witnesses.

JOHN WESLEY CARPENTER.
